ATTORNEY

UNITED STATES PATENT OFFICE

HERBERT A. CUTTING, OF DETROIT, MICHIGAN

CLEANING MEANS

Application filed April 24, 1929. Serial No. 357,649.

One of the primary objects of my invention is to provide a means whereby steam may be supplied and used with a suction or vacuum cleaner for the purpose of aiding in the cleaning of rugs, carpets or the like.

I have found that if steam is supplied at a point adjacent to the suction opening of a vacuum cleaner a most remarkable increased cleaning efficiency is had.

Other objects of my invention are the provision of simple and efficient mechanism by which steam may be produced and supplied to a conventional suction of vacuum cleaner.

With the above and other objects in view, my invention consists in the arrangement, combination and construction of the various parts of my improved device as described in the specification, claimed in my claims and shown in the accompanying drawings, in which:

Fig. 1 is a side elevation of a vacuum cleaner showing my invention applied thereto.

Fig. 2 is a view taken on line 2—2 of Fig. 1.

Fig. 3 is a view, partly in elevation and partly in section, showing in detail the nozzle by which steam is supplied to a vacuum cleaner.

Fig. 4 is a view, partly in elevation and partly in section, showing a water tank and heater such as may be utilized with my invention.

Fig. 5 is a view taken on line 5—5 of Fig. 3.

I have shown more or less diagrammatically a conventional suction or vacuum cleaner which I have generally indicated at 5, having a conventional electric motor 6, foreign matter collector or bag 7, and operating handle 8. The suction inlet for the cleaner will be conventionally located at the forward portion thereof as is indicated at 9.

I provide a bracket member 10, which may be clamped around the housing of the motor 6 by means of bolt and nut, indicated generally at 11, and which supports at one end a container 12, which is adapted to contain water. Water may be supplied to the container 12 by removing the cap 13 thereon.

The bottom of the container 12 has secured thereto a housing 14 containing an electrical resistance unit 15 which may be connected

through suitable wires 16 with a source of electricity. If desired the wires 16 may be connected with the wires 17 which run to the electric motor 6 so that when the motor is operated the resistance unit 15 is likewise operated.

Operation of the unit 15 will cause the water in the container 12 to be heated. When the water has been heated to the point where steam is formed, such steam will pass from the container through the pipe 18, which connects with the top of the container, downwardly into a nozzle member 19 which is located by a bracket 20 directly in front of the cleaner housing and of the suction nozzle 9. Steam passes from the nozzle 19 through the holes 25 in the bottom thereof.

I have found that the use of these holes greatly facilitates an equal distribution of the steam across the entire face of the suction nozzle. Inasmuch as the nozzle member 19 is downwardly directed, it will be readily apparent that steam will be supplied to the floor or carpeting directly in front of the suction nozzle 9 and the combination of the steam and the suction results in a cleaning of the carpeting which is much superior to any results obtained by cleaning without the steam.

As will be readily understood, movement of the vacuum cleaner over the surface being cleaned will result in the cleaner acting upon the surface immediately after it has been treated with steam, and I have found this to result in a much brightened and efficiently cleaned surface.

It will be obvious that various changes may be made in the arrangement, combination and construction of the various parts of my improved device without departing from the spirit of my invention and it is my intention to cover by my claims such changes as may be reasonably included within the scope thereof.

What I claim is:

1. A vacuum cleaner including a housing member and a suction inlet, a water container removably secured to said housing and having an outlet leading to a point adjacent said suction inlet and means for heat-

ing water in said container to supply steam to an article being cleaned.

2. A vacuum cleaner including a housing member and a suction inlet, a bracket secured to said housing member, a water container secured to said bracket and having an outlet leading to a point adjacent said suction inlet and means for heating water in said container to supply steam through the outlet to an article being cleaned.
